UNITED STATES PATENT OFFICE.

HENRY BOUCHARD, OF ST. ELMO, ALABAMA.

CAR-AXLE BOX.

SPECIFICATION forming part of Letters Patent No. 257,648, dated May 9, 1882.

Application filed November 23, 1881. (No model.)

To all whom it may concern:

Be it known that I, HENRY BOUCHARD, of St. Elmo, in the county of Mobile and State of Alabama, have invented a new and Improved Railroad-Car Axle-Box; and I do hereby declare that the following is a full, clear, and exact description of the same, reference being had to the accompanying drawings, forming part of this specification, in which—

10 Figure 1 is an under side view of a railway-car to which my invention is applied. Fig. 2 is a sectional elevation of one of the journal-boxes enlarged. Fig. 3 is a transverse sectional view of the same box in line xx of Fig. 2.

15 My invention relates to improvements in means for preventing car-axle boxes from getting hot; and it consists in the peculiar construction and arrangement of the parts, as hereinafter more fully set forth.

20 In the accompanying drawings, a represent two car-trucks, on which the bottom or floor b of a car rests, all of the usual construction.

25 c represents a rotary fan-blower of ordinary construction, secured to the lower face of the truck, to the nozzle of which blower is secured preferably an india-rubber pipe, d , attached at its outer end to a main air-pipe, e , preferably of metal. The metallic pipe e is secured to 30 the bottom b of the car and passes around its ends and sides parallel thereto, and may be coiled in the middle of the bottom of the car, if desired.

35 g represent branch metallic pipes, hinged to the main air-pipe e , and each provided at its lower end with an india-rubber pipe, z , leading into a pipe, h , opening into car-axle box i , of the usual construction.

40 k represents a grooved pulley, fast on the axis of the rotary fan-blower, around which passes a belt, l , which passes thence around a pulley, m , on one of the car-axles n .

45 o represent branch pipes leading from the main air-pipe e up through the floor of the car into the car, whereby it may be ventilated. If the car is a refrigerating-car, two or more rotary fan-blowers are employed, with pipes leading from the main pipes e through the floor of the car at one or more places, whereby a 50 perfect ventilation will be made in the car

when in motion, thereby preserving fruit, vegetables, and meat a greater length of time than by the usual method without ventilation, and at the same time a current of cold air will be injected into each axle-box to prevent it from 55 becoming heated.

p represents a small axle-box, adapted to fit into any one of the axle-boxes, of ordinary construction. The small axle-box p , inserted in the larger axle-box q , is provided on its inner 60 end with a semicircular bearing, r , for the passage of the axle, and a spring or springs, $s s$, secured to its lower face, the free ends of the springs s bearing against the bottom of the axle-box q , in which the smaller axle-box p is 65 inserted.

$t t$ represent set-screws passing through the bottom of the axle-box q , the points of the screws bearing against the springs s , whereby the tension of the springs may be adjusted. 70 The function of the springs is to keep the lubricant contained in the axle-box p always in contact with the car-axle in its revolution, and thus dispense with the cotton-waste packing or other conveyer of the lubricant to the car-axle 75 in general use.

$u u$ represent flat springs secured to the under face of the small axle-box p and curved outwardly, so that their free ends bear against the inner face of the outer end of the axle-box 80 q , whereby the axle box p is pressed inwardly.

$v v$ represent arms, secured to the sides of the axle-box p and projecting above it, which act as stops to prevent the axle-box p from being raised too high by abutting against the 85 upper face of the axle-box q when the box p is raised.

The lubricant employed may be soft soap or other equivalent cheap material, always kept in contact with the axle, whereby a conveyer 90 or packing for the lubricant is entirely dispensed with.

What I claim as my invention is—

1. The combination, with a rotary fan-blower driven by a belt connected with the shaft of 95 the blower and a car-axle, of the main air-pipe e and branch air-pipes g , each hinged to the air-pipe and leading to an axle-box, and ventilating-pipes o , leading from the main air-pipe e through the floor of the car into its interior, 100

whereby the car-axle boxes are kept cool and the car ventilated at the same time, substantially as described.

2. The combination, with the axle-box *q*, provided with the adjusting-screws *t*, of the axle-box *p*, adapted to be inserted therein, and provided with the stops *v* and springs

s u, secured to the under face, substantially as described, and for the purpose set forth.

HENRY BOUCHARD.
